UNITED STATES PATENT OFFICE

JAMES A. FOLEY, OF OMAHA, NEBRASKA

GARMENT HANGER

Application filed September 11, 1929. Serial No. 391,789.

The invention relates to garment hangers and has for its object to provide a device of this character particularly adapted for use in stores where ladies' garments are constantly removed from their cases for display and vending purposes, and has for its object to provide, in connection with the hanger, pivoted arms terminating adjacent the end of the arched bar, and controlled by the suspending hook in a manner whereby the pivoted arms will be forced into clamping engagement with the garment straps by the weight of the garment thereon, thereby preventing the straps from slipping over the ends of the hanger bar.

A further object is to provide the hanger bar with upwardly extending eyelet members having eyes in the upper ends thereof through which are rockably mounted the pivoted arms, the shaft of the hook being slidably mounted in the bar and pivotally connected with the arms.

A further object is to provide screw eyes of a standard commercial form for the arm engaging members so as to minimize the cost and simplify the construction of the device.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a view in elevation of the hanger showing a garment supported thereon.

Figure 2 is a detail perspective view of the central portion of the hanger.

Figure 3 is a plan view of the outer end of one of the clamping arms.

Referring to the drawings, the numeral 1 designates the arcuate bar, on which the gar-

ment 2 is supported with its shoulder portions 3 extending over the same. It has been found that where hangers are removed from cases or placed therein, the shoulder portions 3 slip over the ends 4 of the arcuate member 1 and drop to the floor. To obviate this difficulty the hanger is provided with outwardly and downwardly extending clamping arms 5, which, when the garment is supported on the bar 1, swing downwardly at their outer ends for forcing the rubber ferrule 6 carried by the angular arm 7 against members 3.

When the ferrules 6 are forced downwardly into clamping engagement with the shoulder members 3, said shoulder members are positively held against slipping from the ends of the arcuate bar 1, therefore it will be seen that the garments may be easily handled, and the garment maintained in position on the hanger.

Secured at 8 to the bar 1 are the upwardly extending eyelet members 9, the arms 5 being rockably mounted through eyes 10 of the said eyelet members 9. The inner ends of the arms 5 are flattened to permit pivotal connection at 11 to a flattened portion of the shaft 12 which is provided with a supporting hook 13. The lower end of the shaft 12 is slidably mounted in a bearing 14 of the bar 1.

From the above it will be seen that a garment hanger is provided which can be cheaply manufactured and one wherein the pivoted arms and suspension hook and shaft are formed from relatively heavy wire, and conventional eyes are used, thereby allowing the device to be formed from standard commercial material.

The invention having been set forth what is claimed as new and useful is:—

A garment hanger comprising a garment receiving bar, transversely disposed arm engaging eyes carried by the said bar, clamping arms rockably and slidably mounted in said eyes, the outer ends of said arms being

provided with garment engaging members, a suspension hook above the bar, a downwardly extending shaft carried by the suspension hook and slidably mounted in a bearing of the bar, said shaft being disposed between the eyes, a pivot connecting the inner ends of said arms and shaft upon opposite sides of the said shaft above the bar whereby upon suspension of the hanger from its hook 10 the outer ends of the said arms will be forced into clamping engagement with the bar.

In testimony whereof I hereunto affix my signature.

JAMES A. FOLEY.
